ELECTRICAL DISTRIBUTION CENTER WITH TIMER CONTROLLED CIRCUITS

Jean O. Reinecke, Chicago, Ill., assignor to Sunbeam
Corporation, Chicago, Ill., a corporation of Illinois

Application September 18, 1958, Serial No. 52,679

Term of patent 14 years

(Cl. D26—13)

Fig. 1 is a front perspective view of an electrical distribution center with timer controlled circuits, showing my new design;

Fig. 2 is a top plan view;

Fig. 3 is a side elevational view, the opposite side being substantially a mirror image thereof;

Fig. 4 is a cross-sectional view taken on line 4—4 in Fig. 1; and

Fig. 5 is a cross-sectional view taken on line 5—5 in Fig. 1.

The dominant features of my new design are shown in solid lines in the drawing.

I claim:

The ornamental design for an electrical distribution

center with timer controlled circuits, as shown and described.
